(57) **CLAIM**

The ornamental design for an electronic device, as shown and described.

DESCRIPTION

FIG. 1 is a perspective view of an electronic device in a 180 degree open configuration, in accordance with the present invention.

FIG. 2 is a perspective view thereof in a closed configuration; FIG. 3 is a perspective view thereof in a 360 degree open configuration;

FIG. 4 is a top plan view thereof;

FIG. 5 is a rear elevation view thereof;

FIG. 6 is a right side view thereof;

FIG. 7 is a front elevation view thereof;

FIG. 8 is a bottom plan view thereof; and,

FIG. 9 is a left side view thereof.
